US0D1011135S

(12) **United States Design Patent** (10) **Patent No.:** **US D1,011,135 S**
(45) **Date of Patent:** **** Jan. 16, 2024**

(54) **CONTAINER**

(71) Applicants: **Jordan Kobayashi**, Kingston (CA);
Morgan Pittfield, Kingston (CA)

(72) Inventors: **Jordan Kobayashi**, Kingston (CA);
Morgan Pittfield, Kingston (CA)

(**) Term: **15 Years**

(21) Appl. No.: **29/811,472**

(22) Filed: **Oct. 14, 2021**

(51) **LOC (14) Cl.** **07-01**

(52) **U.S. Cl.**

USPC **D7/511**; D7/529

(58) **Field of Classification Search**

Primary Examiner — Jae Liang

Assistant Examiner — Tia Ruth-Renee Polidori

(57) **CLAIM**

The ornamental design for a container, as shown and described.

DESCRIPTION

FIG. 1 is a top front side perspective view of a container showing our new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is another right side view thereof, shown with a lid in an alternate position.

The portions of the container shown in dot-dot-dash broken lines form no part of the claimed design.

1 Claim, 4 Drawing Sheets
